UNITED STATES PATENT OFFICE.

AUGUST GRAP, OF BROOKLYN, NEW YORK.

BOTTLE-FILLING APPARATUS.

SPECIFICATION forming part of Letters Patent No. 532,235, dated January 8, 1895.

Application filed November 22, 1893. Renewed November 13, 1894. Serial No. 528,619. (No model.)

To all whom it may concern:

Be it known that I, AUGUST GRAP, a citizen of the United States, residing at Brooklyn, in the county of Kings and State of New York, have invented certain new and useful Improvements in Bottle-Filling Apparatus, of which the following is a specification.

The bottle-filling apparatuses heretofore devised served well the purpose of bottling distilled liquids, but they could not be used for bottling malt liquids owing to the formation of foam, by which the regular working of the apparatus was impaired. Many efforts were made to provide an apparatus by which beer, ale, &c., could be bottled without the formation of foam, but without success.

This invention is designed to furnish a bottle-filling apparatus by which bottles can be rapidly filled without interference by the foam formed in the bottling; and the invention consists of a bottle-filling apparatus which comprises two closed receivers, one being located above the other, the first receiver being connected to the keg or other receptacle which contains the liquid to be bottled, while the second receiver is provided with a number of siphon-tubes, to which the bottles to be filled are applied. The first receiver is provided with a float-valve and connected with the keg containing the liquid to be bottled by a vent-tube, so that the air or gas in the same is automatically returned to the keg. The second receiver is provided with an automatically-operated float-valve by which the supply of liquid from the first receiver is automatically established and interrupted and the quantity of liquid filled into the bottles controlled. The bottles are applied to spring-actuated stoppers on the siphon-tubes and to supporting-bars, said stoppers being connected with the vent of the first receiver by vent-tubes, so that the air in the bottles is transmitted, as the filling proceeds, to the keg from which the liquid is supplied or to the first receiver, as the case may be.

The invention consists further of certain details of construction, which will be fully described hereinafter and finally pointed out in the claims.

In the accompanying drawings, Figure 1 represents a perspective view of my improved

bottle-filling apparatus. Fig. 2 is a front elevation of the closed bottle-filling receiver, with its siphon-tubes, a portion of the same being broken off to show the float-valve at the interior of the same. Fig. 3 is a detail vertical section, drawn on a larger scale, showing the connection of the siphon-tube with the closed receiver. Figs. 4 and 5 are vertical transverse sections of the bottle-filling receiver, showing the same respectively in the act of filling a bottle, and after the bottle is removed from the siphon-tube. Fig. 6 is a detail front elevation of the foam-collecting receiver, a portion of the same being broken off to show the interior construction, and Fig. 7 is a diagram, said diagram showing the connection of the bottle-filling apparatus with the keg or barrel from which the liquid is to be supplied.

Similar letters of reference indicate corresponding parts.

Referring to the drawings, A and A' are the two closed receiving vessels, which are made of cylindrical, oval or other cross-section, and preferably constructed of copper, galvanized sheet-iron or other suitable material. The heads a, a' are riveted to the flanged bodies of the receivers A, A', and tightly connected with the same by suitable packing-rings. Both receivers A, A', are mounted on a supporting-frame B, the receiver A being supported at a greater elevation than the receiver A' and connected by pipe b with the keg or other receptacle X, the liquid from which is to be bottled. A second pipe b' leads from the head of the upper receiver A to the lower part of the lower receiver A', said pipe being provided with a stop-cock b² so as to turn on or close the communication with the upper receiver A.

The upper receiver A is provided intermediate between the inlet pipe b and the outlet-pipe b' with a suitable strainer d that serves for collecting the foam which is formed in the receiver A, so as to prevent the same from passing to the lower receiver A'. A float-valve D is guided by suitable brackets d' in the upper part of the upper receiver A, said float-valve serving to close an outlet-pipe D' that is connected by a tube D² with the vent-bung of the keg or other reservoir X from which the liquid is drawn. When a suf-

ficient quantity of liquid is supplied to the receiver A so that the float-valve D of the same is raised for closing the outlet-tube D', no air or carbonic acid gas which accumulates 5 in the upper part of said receiver can pass to the keg or other receptacle X, so that by the counter-pressure of the aeriform fluid in the upper part of said receiver, the supply of liquid thereto is automatically interrupted 10 until a sufficient quantity is drawn from the same into the lower receiver A', whereby the float-valve D is lowered and opens the outlet-tube D', and the air and gas accumulated in the upper part of the receiver A' can pass off 15 again.

The lower receiver A' is provided with a number of siphon-tubes E, which are connected in an air-tight manner thereto, as shown in Fig. 3, said siphon-tubes having a 20 certain play at their point of connection with the lower receiver A', permitted by the construction to be hereinafter described. The lower ends of the inner legs of the siphon-tubes E are curved so as to form contact with 25 a small plate or strip of rubber e, which is applied to the bottom of the receiver A', said plate or strip serving for the purpose of closing the lower ends of the inner legs of the siphon-tubes when no bottle is applied to the 30 outer legs of the same. The outer legs of the siphon-tubes E are connected by helical springs e' with a fixed horizontal bar e² arranged above and extending longitudinally of the top part of the receiver A', and are 35 provided with sliding and spring-actuated stoppers f which are arranged on said legs and are adapted to close the bottles to be filled, when they are placed over said exterior legs. By inserting the exterior legs of the 40 siphon-tubes into the bottles, the spring-actuated stoppers f are pushed back against the tension of their springs f^x until the rim of the bottle-mouth arrives at the next horizontal rest or bar f', which is arranged at the 45 front part of the receiver A', as shown in Figs. 1 and 2.

The connection of the siphon-tubes E with the receiver A' is made by means of a longitudinally arranged packing-plate e³, which is 50 retained on the outside of said receiver by means of a slightly-curved metallic plate e⁴ attached by screw-posts e⁵ to the top of the receiver, as shown in Fig. 3. The openings in the receiver A' and in the covering-plate e⁴ for each siphon-tube are made somewhat 55 larger than the opening in the packing-plate or strip e³. On each siphon-tube E is arranged, at the point where it passes into the receiver A', a sleeve e⁶, which passes through 60 the openings in the receiver, elastic-plate and clamping-plate, and is provided with a flange e⁷ at one end, and with an exterior screw-thread at the lower end. The flange e⁷ rests on the upper side of the packing-plate e³, and within 65 the opening of the clamping-plate e⁴, while an elastic ring or washer e⁸ is applied to the lower side of the same, the latter being tightly

pressed against the packing-plate by means of a screw-nut e⁹, so that said packing-plate and the ring e⁸ are held between the collar e⁷ 70 of the sleeve e⁶ and the tightening screw-nut e⁹, whereby a tight connection between the siphon-tube E and the receiver A' is obtained and the former thereby left free to oscillate on the receiver, so that its lower inner end may be 75 applied to or removed from the elastic plate e at the bottom of said receiver. When a bottle is placed on the exterior leg of a siphon-tube E and hung onto the bottle rest or supporting-bar f', the weight of the bottle overcomes 80 the tension of the spring e' and causes the oscillating of the siphon-tube on its connection with the packing-plate e³, so that the inner end of the siphon-tube is moved away from the elastic plate e, as shown in Fig. 4. 85 The liquid passes through the siphon-tube into the bottle until the liquid in the bottle is on a level with that in the receiver A', when the supply to the bottle is interrupted. The bottle is then removed for being closed. As 90 soon as the filled bottle is removed from the bottle-rest or supporting-bar f', the spring e' raises the outer leg of the siphon-tube and presses the inner end of the same against the elastic-plate e, so that the siphon-action is 95 thereby interrupted.

The lower receiver A' is provided at the inner end of the supply-tube b' with a float-governed valve g, the spindle of which is guided in suitable bracket-arms g^x at the interior of 100 said receiver. A safety valve g' is arranged at the top part of the receiver A', said safety-valve being set to a certain pressure so that whenever the body of air or gas accumulated in the upper part of such receiver is under 105 too great a pressure, a quantity of the air or gas can escape until the desired pressure is established. The liquid is supplied from the upper receiver A, and, as it rises in the lower receiver A', it gradually lifts the float g² of 110 the valve g and closes said valve when the level of the liquid arrives at its maximum height. As soon as any part of the liquid in the receiver A' is drawn off by the siphon-tubes, the level of the liquid in the same falls 115 and the supply-valve g is automatically opened, so that a supply of liquid is established. When, by the quick removal of the bottles from the siphon-tubes, the quantity of liquid withdrawn from the receiver A' is 120 equal to that supplied to the same from the upper receiver A, the level of the liquid remains at the required point, so that the liquid is continuously supplied without the closing of the valve g. An experienced bottler 125 can connect the bottles with the siphon-tubes and remove the filled bottles successively at such a speed that hardly any interruption in the supply of liquid to the receiver takes place. 130

The stopper f on each siphon-tube E, which closes the mouth of the bottle while the filling action takes place, is connected by a small vent-tube f² with the outlet-pipe D' of the up-

per receiver A, so that the air in the bottles is conducted through the vent-tubes f^2 , either into the upper part of said receiver, or, when the float-valve D is closed, through the outlet-tube directly to the keg from which the liquid is supplied.

By referring to Fig. 7 it will be observed that the keg is supported at a higher elevation than the receiver A, so that the liquid is supplied under pressure to the latter and from the same to the lower receiver A'.

If desired, the pressure in the keg may be increased by a suitable pump, so that the lower receiver A' is always supplied with liquid up to the required level, until the supply is automatically interrupted by the action of its float-governed valve g.

The operation of my improved bottling-apparatus is as follows: A number of bottles are properly cleaned and placed near the apparatus. One after the other is placed on the exterior legs of the siphon-tubes E and supported by its neck on the bottle rest or supporting-bar f', located between the receiver A' and said legs. By the weight of the bottle, the siphon-tube is oscillated and the inner end thereof moved away from the elastic-plate e of the receiver A', so that the filling action immediately commences. The supply of liquid to the bottle is continued until the level of the liquid in the neck of the bottle is equal with the level of the liquid in the receiver A', when the further supply of liquid is automatically interrupted, as the liquid in the neck of the bottle cannot rise above the liquid in the receiver. Consequently no spilling of liquid in filling the bottles takes place. The bottle is then removed from the exterior leg of the siphon-tube and the liquid in said leg is discharged into the bottle while the same is removed, so that every bottle is filled exactly to the required extent, ready for corking. The next bottle is then placed on the exterior leg of the siphon-tube and filled in the same manner. As the foam and surplus pressure of the liquid is removed from the same by its passage through the upper receiver A, no foaming takes place in the lower receiver A', so that consequently the bottles can be filled by being hung in succession on the exterior legs of the siphon-tubes, the supply of liquid keeping pace with the filling, so that the filling action takes place with great rapidity, and a skilled bottler is able to fill a large number of bottles within a given time. When the bottles give out, the supply of liquid to the receiver A' is interrupted by the closing of its float-valve g, which closes the supply-pipe b' in a reliable and automatic manner. When the filling of the bottles is to be continued, they are again hung on the exterior legs of the siphon-tubes E, whereby the level of the liquid in the receiver A' is lowered again and thereby the supply-valve g opened so that the supply of liquid to the lower receiver from the upper receiver is resumed. By the arrangement of the up-

per foam-retaining receiver A, which is interposed between the lower bottle-filling receiver A' and the keg from which the liquid is supplied, the clogging of the bottle-filling apparatus by the foam generated by the passing of the beer or other fermented liquid through the receiver is prevented, and thereby the operation of the apparatus rendered reliable and effective.

The apparatus is also adapted, when built on a larger scale, to the racking-off of beer or other fermented liquids from storage-casks in breweries to the shipping kegs by which the beer is sent to the customers. In this case, one keg after the other is applied to the siphon-tubes and filled by the apparatus in the same manner as the bottles, the kegs being then bunged as soon as filled, so that the racking-off of beer into the shipping kegs is thereby greatly expedited and connected with less difficulty than the methods at present in use.

Having thus described my invention, I claim as new and desire to secure by Letters Patent—

1. The combination of an upper foam-retaining receiver adapted to be connected with the keg or other receptacle containing the liquid to be bottled, a gas-outlet-pipe connected with said receiver, a float-governed valve for automatically closing said pipe, the float of said valve being located in said receiver, a second receiver located below the first receiver and connected therewith by a supply-pipe, one or more siphon-tubes arranged in the lower receiver and adapted to receive the bottles on the exterior leg of the same, and means for automatically opening or closing the inner end of the supply-pipe, substantially as set forth.

2. The combination, of an upper foam-retaining receiver adapted to be connected with the keg or other receptacle containing the liquid to be bottled, a strainer at the lower part of said receiver, a second receiver located below the foam-retaining receiver, a supply-pipe connecting the upper receiver below the strainer to the lower receiver, one or more siphon-tubes arranged in the lower receiver and adapted to receive the bottles, and means for automatically opening or closing the inner end of the supply pipe, substantially as set forth.

3. The combination of a foam-retaining receiver connected with the keg or other receptacle containing the liquid to be bottled, a valved gas-outlet-pipe in said receiver a strainer at the lower part of said receiver, a second receiver located below the foam-retaining receiver, a supply-pipe connecting the upper receiver below the strainer to the lower receiver, one or more siphon-tubes arranged in the lower receiver and adapted to be oscillated by the bottles, so as to supply the liquid to the same, and an automatically operated float-governed valve at the inner end of the supply-tube of the lower receiver, substantially as set forth.

4. The combination of a foam-retaining receiver provided with a valved-gas-outlet-tube connected with the keg or other receptacle from which the liquid is supplied, a second receiver located below the first receiver, a supply-pipe connecting the upper receiver with the lower receiver, one or more siphon-tubes arranged on the lower receiver and provided with stoppers and vent-tubes connecting the stoppers with the gas-outlet-pipe of the upper receiver, substantially as set forth.
5. The combination with a filling-receiver provided with one or more oscillating siphon-tubes, of a packing for each siphon-tube at the point where it leaves the receiver, said packing consisting of a packing-plate suitably retained on the outside of the receiver, a screw-threaded flanged sleeve on the siphon-tube, and a screw-nut on said sleeve, between which nut and the flange of said sleeve the packing-plate is clamped, substantially as set forth.

6. The combination with a filling receiver provided with one or more oscillating siphon-tubes, springs for connecting the siphon-tubes with a fixed bar on said receiver, means for closing the inner ends of the siphon-tubes when they are swung outwardly by said springs, of a packing for each siphon-tube at the point where it leaves the receiver, said packing consisting of a packing-plate attached by a covering-plate to the top part of the receiver, a screw-threaded sleeve on the siphon-tube a screw-nut on said sleeve and a washer interposed between the elastic plate and the screw-nut, substantially as set forth.

In testimony that I claim the foregoing as my invention I have signed my name in presence of two subscribing witnesses.

AUGUST GRAP.
